UNITED STATES PATENT OFFICE.

JOHN M. BARNES, OF WACOUSTA, ASSIGNOR OF ONE-HALF OF HIS RIGHT
TO WESLEY S. PALMER, OF LANSING, MICHIGAN.

WINDMILL.

SPECIFICATION forming part of Letters Patent No. 223,465, dated January 13, 1880.

Application filed November 1, 1879.

To all whom it may concern:

Be it known that I, JOHN M. BARNES, of Wacousta, in the county of Clinton and State of Michigan, have invented certain new and useful Improvements in Windmills; and I do hereby declare the following to be a full, clear, and exact description thereof, reference being had to the accompanying drawings, making part of this specification, and in which—

10 Figures 1 and 2 are perspective views of a windmill with my improvements attached. Fig. 3 is a vertical section of same.

My invention relates to that class of windmills wherein the face-pressure automatically 15 controls the pitch of the blades; and it consists in sundry details of construction, as hereinafter more specifically described and claimed.

To enable others skilled in the art to make and use my invention, I will proceed to 20 describe the exact manner in which I have carried it out.

In the drawings, A represents the base, and B the vertical supports, connected together by metallic ring brackets or plates b b', through 25 and upon which the turn-table C is mounted, it being secured from vertical movement by means of the flanges and the set-screw c².

D represents the crank-shaft, near one end of which is mounted the wind-wheel E, said 30 shaft being journaled in suitable bearings c c', formed on the sides of the turn-table, the bearing c' being extended outward to form a bearing, c³, upon which is secured the vane F.

d represents a rod forming a pivoted connection between the crank-shaft D and the vertical shaft G, which passes down through the turn-table. This shaft G is made in two sections, g g', connected together by a swivel-joint or ball-coupling, g², the lower section being made square and passing through a square hole in the cross-plate b², thus permitting a 35 free vertical movement of the shaft G and a revolving movement of the upper section, g, as the turn-table is revolved, turning the wind-wheel always in the proper direction to the wind.

H represents a circular disk provided with a series of grooves, h, on its outer face, in which the inner ends of the radial arms h' are 40 secured, and to said arms are rigidly secured the stationary inner and outer annular rims,

h² h³, in which the wind or fan blades i are pivoted. The upper and inner ends of said fan-blades are also pivoted to the outer movable annular rim, i'. Two of the wind or fan blades, directly opposite each other, are provided with crank-arms j j on their inner ends, which are connected, by rods k k, with movable levers and collar k', loosely mounted on the shaft D.

L represents an elbow forked-arm lever, pivoted in the upper end of the curved uprights l l, the forked arm of said lever engaging with an annular slot in an independent sliding hub, y, on shaft D, the long arm or free end of the lever being provided with an adjustable weight, l', secured in any desired position upon said arm by a set-screw, l².

M represents a cord having one end secured to a lug, m, on the forked arm of lever L, and passing over a pulley, m', and thence down through the turn-table and through the lower section, g', of the shaft G, said cord being for the purpose of throwing the mill out of gear.

N represents a series of short brace-rods rigidly secured at their outer ends to near the center of the radial arms h', and their inner ends secured to an adjustable collar, n, mounted on the end of the shaft D.

By my improved construction of mill different velocities of wind will not affect the motion of the wind-wheel, and the wind, striking the fans at an angle, straightens them so as to cut the wind, and this operates the weighted lever through the medium of the two wind or fan blades connected therewith, keeping a steady motion and working said lever up and down, thus controlling the motion.

I am aware that windmills have heretofore 90 been made wherein the pitch of the blades is automatically controlled by means of the entire wheel moving on the shaft and provided with connecting-levers to raise a weight.

I am also aware that wind-wheels have heretofore been made wherein an independent sliding hub has been given a torsional movement around the shaft by means of the face-pressure and said independent hub raising a weight as the blades open for relief from the face-pressure, and hence I do not broadly claim either the controlling the pitch by the face-

pressure or controlling the pitch by an independent hub moving on the shaft; but,

Having thus described my invention, what I claim as new, and desire to secure by Letters Patent, is—

In a wind-wheel having the pitch of the blades automatically controlled by the face-pressure, the independent hub *y*, sliding longitudinally on the main shaft, and engaging with a weighted lever, *L*, and the independent

lever-arms *K'*, sliding longitudinally on the shaft, in combination with the crank-arms *j j'* pivoted blades *i i'*, movable rim *v*', and fixed rims *h²* and *h³*, all constructed, arranged, and operated as set forth.

JOHN M. BARNES.
